ISAAC A. BACKLUND, OF CHICAGO, ILLINOIS, ASSIGNOR TO CARRICK ENGINEERING CO.,
OF CHICAGO, ILLINOIS, A CORPORATION OF ILLINOIS.

BOILER-PRESSURE REGULATOR.

1,276,003.

Specification of Letters Patent. Patented Aug. 20, 1918.

Application filed May 3, 1916. Serial No. 95,140.

To all whom it may concern:

Be it known that I, ISAAC A. BACKLUND, a citizen of the United States, residing at Chicago, in the county of Cook and State of Illinois, have invented certain new and useful Improvements in Boiler-Pressure Regulators, of which the following is a specification.

This invention relates to damper-controlling apparatus for steam boilers; and its object is the provision of improved means under the control of steam pressures obtaining in a boiler, for regulating the action of a damper whereby the combustion within the boiler furnace may be governed to generate more or less steam and maintain the steam at a practically uniform pressure.

With these ends in view, the invention consists in the novel construction, adaptation and combination of parts, as will be hereinafter described and claimed.

In the accompanying drawings, Figure 1 is a view partly in elevation and partly in vertical section, of apparatus embodying the present invention. Fig. 2 is a vertical sectional view to an enlarged scale of the water controlling valve shown in a different position from that in which it is represented in the other view.

Referring to the drawings, the numeral 5 designates a portion of a boiler with pipe connections 6 and 7 respectively communicating with the interior of the boiler above and below the water level thereof, which is indicated by W. Said pipe connections constitute branches of a pipe 8 which communicates by means of a T-fitting 8¹ and a nipple 8² with the upper end of a tank 9.

Shut-off cocks 6¹ and 7¹ are provided for the aforesaid connections 6 and 7 to admit water or steam into said tank, as may be desired. Said tank is desirably provided with a depending portion in the nature of a pipe 10 of relatively small diameter, and extending axially therein to within a short distance of the bottom of said extension is the lower end of a tube 11 which is open at both ends. At its upper end this tube is provided with a flexible extension 11¹ which is connected to the lower end of a receptacle 12 the latter being supported upon a rod 13 which, in turn, is supported by being pivotally connected at 14 to an arm 15 of a lever whose other arm 15¹ carries in an adjusted

position a counterweight 16 which serves to 55 retain the receptacle in its uppermost position when the same is empty.

Said lever is fulcrumed at 17 to a column 18 which, as shown, is comprised of a plurality of pipe elements including the aforesaid nipple 8².

19 represents a hydraulic cylinder rigidly secured to a stationary support, indicated by 20, and is connected by a pipe 21 with a side outlet 22¹ of the casing 22 of a so-called three-way rotary valve 23 which may be actuated to establish communication between the cylinder pipe 21 and either of the pipe connections 24 or 25.

The pipe connection 24 is connected by a 70 pipe 24¹ to a supply of water under pressure such, for example, as a city water main. The other pipe connection 25 is provided with an extension 25¹ through which waste water is discharged.

Operable through a packing-box 26 provided on said hydraulic cylinder is a plunger 27 whose protruding end is secured to a sash 28 which is guided for vertical movements with the plunger by a rod 29 secured to the cylinder and passing through an aperture provided in the sash element 28¹. The lower end of said sash is connected by a link or chain 30 to a lever 31 which is fulcrumed at 32 and is connected by a chain 33, passing over a guide sheave 34, with an arm 35 of a bell-crank lever 35¹ secured to the spindle 36 which serves as the pivotal support for the stack damper 37.

38 represents a weight carried by lever 35¹ 90 and tends to hold said damper in its open position.

The aforesaid valve 23 is provided with an operating arm 39 adapted to be swerved to rotatably move the valve through the instrumentality of wiper fingers 40 and 41 secured to a rod 42 which is connected by a pin 43 to lever arm 15 and extends through a guide 42¹.

A charge of liquid, preferably mercury, is 100 supplied to the tank 9 and may be supplemented by water admitted from the boiler by opening the valve 7¹. When the steam pressure within the boiler exceeds that for which the apparatus is regulated, it will act 105 upon the liquid surface in tank 9 to force the mercury upwardly through tube 11 into receptacle 12 until the weight of the mer-

cury in the latter is sufficient to overbalance the power of counterweight 16, whereupon the lever 15—15¹ will be influenced to lower the rod 42 and the fingers 40 and 41 thereof. 5 In such movement, the finger 40 engages the arm 39 to rotate valve 23 so as to afford communication between water supply pipe 24¹ and the pipe 21 for the flow of water under pressure into the hydraulic cylinder 10 to accordingly effect the upward movements of the plunger 27 and sash 28 and thence act through the media of lever 31 and connections 30 and 33 to operate lever 35¹ for closing damper 37. 15 When this occurs, the fire in the boiler furnace is checked with a consequent lessening in the generation of steam until the steam pressure is reduced below what is requisite to support the column of mercury 20 in tube 11 and receptacle 12, whereupon the mercury escapes from the receptacle and enables the counterweight 16 to assert its power and influence the lever 15—15¹ to impart upward movement to the fingers 40 and 25 41 whereby the finger 41 will engage the arm 39 to rotate valve 23 into open communication between the waste pipe 25 and the pipe 21. Under such conditions, the water escapes from the cylinder, the plunger and 30 sash descend, and the weight 38 effects the opening of the damper with an increasingly rapid production of steam.

Included in the invention are appliances for regulating the action of the apparatus 35 so far described which might be termed a governor and serving moreover, to render the apparatus capable of readily overcoming the inertia of the aforescribed movable parts while regulating the action of the 40 same to shut off and reopen the draft before the boiler pressure appreciably rises above and falls below that for which the apparatus is adjusted with an assurance of a practically constant steam pressure.

45 For these purposes, I secure a hollow tubular member 47 in parallel relations to the lever 15—15¹ by supporting the end *a* thereof in an aperture 48 of the weight 16 and from near the other end *b* in the lever 50 standard 41.

Within said member is provided a quantity of mercury, indicated by 49.

50 represents a relatively heavy bar supported from an end 44 of a chain or cable 45 55 which passes over guide sheaves 46 and 46¹ and has its other end connected to the plunger 27. The bar 50 is provided with a slot 51 to accommodate a stud 52 provided on the lever arm 15¹, said stud being engageable by pins 53 or 53¹ disposed in holes provided above and below the stud.

In operation, an upward movement of the plunger 27 caused by an increase in the boiler pressure, as before explained, will effect the lowering of the bar 50 until the pin

53 encounters the stud 52 whereupon the weight of the bar will coöperate with the counterweight 16 to overcome the opposing weight of mercury in receptacle 12 and that in the end *b* of the member 47. 70

When the plunger descends, the bar 50 ascends, whereupon the pin 53¹ becomes operative to tilt the lever 15—15¹ in the contrary direction—that is to say, from the dotted line position *a* to the position in 75 which it is represented by full lines in Fig. 1.

It is apparent that when the weight of the member 50 is added to weight 16, it imparts to the lever 15—15¹ an initial movement 80 which brings it back to substantially its original position as shown in full lines in Fig. 1.

The office of the bar is to coöperate with or oppose the force due to the action of the 85 mercury in receptacle 12 to overcome the inertia of the movable parts and effect the initial movements of the referred-to lever and the member until the mercury therein can flow to the opposite end of the same, 90 thereby asserting its power to rapidly complete the respective tilting movement of the lever, and a quick change in the position of the valve.

From the foregoing, it is evident that the 95 damper 37 opens or closes with relatively slow initial movements so that the fire may be correspondingly accelerated or checked.

What I claim, is—

1. In apparatus of the class described, a 100 steam boiler, a draft-regulating device, a hydraulic cylinder, a plunger therefor, water pipe connections, a valve therefor, a lever operatively connected to said valve and influenced by steam pressures obtaining 105 within said boiler whereby water is caused to be admitted to or discharged from the cylinder to actuate said plunger, a member containing liquid operating with said lever, and a slotted bar operatively connected to 110 said plunger and engageable with the lever and coöoperating with the weight of the liquid within said member to accelerate the action of the valve in controlling the flow of water to and from said cylinder. 115

2. In apparatus of the class described, the combination with a steam boiler, a draft-regulating device therefor, a liquid-containing tank, pipe connections between the upper end of the tank and the steam space within 120 the boiler, a liquid receptacle, connections including a flexible member making communication between the lower end of said tank and the receptacle, a lever supporting said receptacle for vertical movements, and 125 means tending to elevate said receptacle, a cylinder, a plunger therefor, operative connections between the plunger and said draft device, a three-way valve, a pipe connecting the cylinder with the valve, a water-supply 130

- pipe and a water-waste pipe connected with the valve, and operative connections between said lever and the valve whereby the latter is influenced to admit a quantity of water 6 into the cylinder to start the action of said plunger for operating said draft devices when an increase of the steam pressure within the boiler affects the receptacle to cause the same to descend and serving to influence the valve to start the release of water 10 from the cylinder when the boiler pressure decreases below what is necessary to retain the liquid in said receptacle, of means operatively connected with said plunger and engageable with said lever and serving to supplement the power afforded by the weight of liquid which is supplied by the boiler pressure to said receptacle.
3. In a boiler pressure regulator, the combination with a boiler and combustion regulating apparatus, of gravity operated means and means which acts against said gravity operated means, an element displaceable by steam pressure of the boiler for moving 20 the gravity operated means, a power supplying medium control shifted by the gravity operated means, the movement of which supplies the said medium for moving the combustion regulating apparatus and the means which act against said gravity operated means to restore said gravity operated means to approximately its position before it was shifted whereby a predetermined variation in the boiler pressure will shift 30 said power supply medium control in the opposite direction, thereby releasing said medium.
4. In a boiler pressure regulator, the combination with a boiler and combustion regulating apparatus, of gravity operated means and means which acts against said gravity operated means, an element displaceable by steam pressure of the boiler for moving the gravity operated means, a power supplying 40 medium control shifted by the gravity operated means, the movement of which supplies the said medium for moving the combustion regulating apparatus and the means which act against said gravity operated means to 50 restore said gravity operated means to approximately its position before it was shifted whereby a predetermined variation in the boiler pressure will shift said power supplying medium control in the opposite direction thereby releasing said medium, and means for accelerating said movement.
5. A regulator for controlling combustion in steam boiler furnaces comprising means displaceable by pressure of steam in a boiler, 60 gravity operated elements moved by said means, a combustion controlling member, a device for moving the combustion controlling member, a power supplying medium for said device, a control for the power supplying medium actuated by said elements whereby power is supplied and released, means operated by the device for moving the combustion controlling member acting against gravity of said elements for restoring said elements to approximately the position they occupied prior to their first mentioned movement and means for restoring said gravity operated elements to their first mentioned position when the boiler pressure is reduced beyond a predetermined degree.
6. A regulator for controlling combustion in steam boiler furnaces comprising means displaceable by pressure of steam in a boiler, gravity operated elements moved by said means, a combustion controlling member, a device for moving the combustion controlling member, a power supplying medium for said device, a control for the power supplying medium actuated by said elements, whereby power is supplied and released, means operated by the device for moving the combustion controlling member, acting against gravity of said elements for restoring said elements to approximately the positions they occupied prior to their first mentioned movement, means for restoring said gravity operated elements to their first mentioned position when the boiler pressure is reduced beyond a predetermined degree and means for accelerating said movement.
7. A regulator for controlling combustion in steam boiler furnaces, a tank having communication with the boiler, a movable receptacle in an elevated position in communication with the tank, means of communication between the tank and receptacle whereby fluid in the tank may be forced into the receptacle by the pressure in the boiler, an oscillatable member to which the said receptacle is connected near one end, a weight connected to the lever near its opposite end, a rod connected to said lever at the end to which the first mentioned member is connected, valve operating elements on the said rod spaced apart from each other, a combustion control, a pressure operated device for moving the combustion control, a valve for admitting pressure to said pressure operated device and for releasing said pressure, connections for delivering pressure and for releasing pressure to said pressure operated device, means whereby the movement of the valve operating elements communicates motion to the valve when the weight of material in the receptacle overcomes the gravity of the mechanism for operating the valve, means whereby the pressure operated device restores the said receptacle and the parts connected to it to approximately the position it occupied prior to its first mentioned movement, a gravity element associated with the lever for applying power to said lever when the gravity element shifts from one side to the other of the pivot of said lever and supplementing the action of the weight

associated with said lever to accelerate the movement of the valve operating mechanism when pressure in the boiler has varied a predetermined degree, thereby shifting the valve to release the pressure in the pressure operated device and gravity operated means for restoring the combustion controlling member.

8. In a boiler pressure regulator, the combination with the boiler, of a combustion regulating apparatus, a mercury receptacle, a pressure chamber connected with said boiler and said mercury receptacle, a valve, rods connected to the mercury receptacle which actuates said valve, a pressure cylinder, a piston therein which is connected to the combustion regulating device, a governor to impart initial movement to said rod, said governor being connected to the piston of the pressure cylinder to restore said rods to approximately their position before they were shifted, whereby a predetermined variation in the boiler pressure will shift said

rods in the opposite direction, and means to accelerate the movements of said governor. 25

9. In a boiler pressure regulator, the combination with the boiler, of a combustion regulating apparatus, a mercury receptacle, a pressure chamber connected with said boiler and said mercury receptacle, a valve, rods connected to the mercury receptacle which actuates said valve, a pressure cylinder, a piston therein which is connected to the combustion regulating device, an oscillating tube which is connected to the piston 35 of the pressure cylinder to impart initial movement to said rods to restore said rods to approximately their position before they were shifted, whereby a predetermined variation in the boiler pressure will shift said 40 rods in the opposite direction and a movable medium in said tube to accelerate the movements of said tube.

Signed at Chicago, Illinois, this 25th day of April, 1916.

ISAAC A. BACKLUND.
